234,090

TOY TRUCK WITH MOVABLE RAMP OR THE LIKE

Jerrold J. Krumholz, West Orange, and Herbert Happe
Van Reisgen, Westfield, N.J., assignors to Victor
Comptometer Corporation, Chicago, Ill.

Filed Jan. 22, 1973, Ser. No. 325,662

Term of patent 14 years

Int. Cl. D21—01

U.S. Cl. D34—15 AJ

Fig. 1

Fig. 2

Fig. 3

Fig. 4

FIG. 1 is a perspective view of a toy truck with movable ramp showing our new design;

FIG. 2 is a top plan view thereof;

FIG. 3 is a side elevational view thereof; and

FIG. 4 is a front elevational view thereof showing the ramp in a raised position.

We claim:

The ornamental design for a toy truck with movable ramp or the like, as shown and described.
